US00D829816S

(12) **United States Design Patent** (10) Patent No.: **US D829,816 S**
(45) Date of Patent: ** Oct. 2, 2018

(54) **INK CARTRIDGE**

- (71) Applicant: **BROTHER INDUSTRIES, LTD.**,
Nagoya-shi, Aichi-ken (JP)
- (72) Inventors: **Hiroaki Takahashi**, Nagoya (JP);
Toshiya Inada, Nagoya (JP); **Masahide
Asano**, Nagoya (JP)
- (73) Assignee: **BROTHER INDUSTRIES, LTD.**,
Nagoya (JP)
- (**) Term: **15 Years**
- (21) Appl. No.: **29/614,125**
- (22) Filed: **Aug. 16, 2017**

(30) **Foreign Application Priority Data**

(57) **CLAIM**

The ornamental design for an ink cartridge, as shown and described.

DESCRIPTION

FIG. 1 is a front perspective view of an ink cartridge;

FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof;

FIG. 8 is a rear perspective view thereof; and,

FIG. 9 is bottom perspective view thereof.

The evenly spaced broken lines depict environmental subject matter only and form no part of the claimed design.

1 Claim, 8 Drawing Sheets
